UNITED STATES PATENT OFFICE

2,280,094

TABLE TOP CONSTRUCTION

Sern Madsen, Clinton, Iowa, assignor to Curtis Companies Incorporated, Clinton, Iowa, a corporation of Iowa

Application April 10, 1939, Serial No. 266,974

2 Claims. (Cl. 311—4)

One object of my present invention is to provide a table top construction particularly adapted for installation as a sink supporting counter in a kitchen or the like wherein the counter or table top is made in sections.

This application is a continuation in part of my copending application, which became Patent No. 2,158,467 on May 16, 1939.

Another object is to provide a table top construction to which a sink may be attached and the joints between sections of the table top are so formed that there are no visible screws or other fastening means except in one modification of a joint construction, wherein the heads of the screws are visible.

A further object is to provide a joint between sections of the table top which has a splice bar mounted on top of the adjacent ends of two sections of the table top, a splice plate being provided beneath the sections and the bar and plate being connected together by clamp screws.

Still a further object is to provide the splice plate with upturned and inclined flanges which coact with grooves in the bottom of the sections of the table top in such manner as to tend to pull the sections toward each other.

With these and other objects in view, my invention with respect to its features which I believe to be novel and patentable will be pointed out in the claims appended hereto. For a better detailed understanding of the invention, reference is made to the following description and to the accompanying drawing, in which

Figure 1 is a plan view of a table top construction embodying my invention;

Figure 2 is an enlarged sectional view on the line 2—2 of Figure 1 showing a splice between sections of the table top;

Figure 3 is an exploded perspective view of the elements of the splicing means;

Figure 4 is a sectional view similar to Figure 2 showing a modified construction, and

Figure 5 is a similar sectional view showing another modified construction.

On the accompanying drawing, I have used the reference numeral 10 to indicate one section of a table top. Other sections thereof are indicated at 13 and 14. A back splasher 26 is used in connection with the table top sections 10, 13 and 14 when the table top is installed as a counter or work table in a kitchen or the like. The walls of the kitchen are indicated at 16.

The table top sections 10 and 14 are joined to the corner section 13 by splice bars 17. The splice bars 17, as shown in Figure 2, are of

T-shaped cross section having arms 18 and a leg 19. The leg 19 is screw threaded to receive clamping screws 20.

The leg 19 is located between the table top sections and a splice plate 21 is engaged with the lower surfaces thereof by the clamp screws 20. The splice plates 21 have their edges 22 upturned to provide inclined flanges which are received in transverse grooves 23 formed in the bottom surfaces of the top members 13 and 14.

A banding frame F is provided to line a sink opening 24 in the top member 10. A sink S is supported by the banding frame F in the manner fully described in my parent application hereinafter referred to.

The table top is covered with linoleum indicated at 28, if desired, and the splice bar 17 is preferably countersunk therein so that the upper surface of the splice bar and the upper surface of the linoleum are flush with each other. It will be obvious that the clamp screws 20 in conjunction with the splice bar 17 and the splice plate 21 (particularly the inclined flanges 22 thereof) cooperate to normally clamp the adjacent edges of the table top sections between them to thereby provide in effect an integral rigid top member with the flanges 22 tending, by their engagement with the edges of the grooves 23, to pull the adjacent top members 10 and 14 toward each other as the clamping screws 20 are tightened.

In the modification shown in Figure 4, some parts are similar to those already described in connection with Figure 2 and bear the same reference numerals with the addition of the letter a. The splice bar 17a is flat instead of being T-shaped, and the clamp screws 20a are welded thereto. The clamp screws extend through the clamp plates 21a and nuts 20' are threaded on the clamp screws to tighten them in position.

Similarly, in Figure 5 the parts have the same reference numerals with the addition of the letter b and instead of the clamp screws 20a being in the form of studs, as in Figure 4, they are countersunk bolts with their heads indicated at 25. The heads 25 are countersunk type and are received in countersunk openings 26 of the splice bar 17b. If desired, the edges of the bar 17b may be provided with prongs 17c to enter the linoleum 28 and more firmly hold it in position.

In accordance with the provisions of the patent statutes, I have described the principle of operation of my invention together with illustrations thereof which I consider to represent its best embodiments. I desire to have it under-

stood, however, that the structures disclosed are illustrative only and that the invention may be carried out by other means provided they come within the scope of the claims.

What I claim as new and desire to secure by Letters Patent of the United States is:

1. In a table top, a plurality of top members and means for splicing the ends of said top members together comprising a T-shaped splice bar having its arms on top of the top members and its leg between them, said leg being thicker than said arms and having tapped openings spaced longitudinally therealong, a splice plate under said top members, said splice plate having the edges thereof inclined towards said top members, said top members having grooves to receive said edges with the inclined surfaces of said splice plate edges engaging the corners of said grooves, and clamp screws extending through said splice plate and into said tapped openings of said leg of said splice bar to draw the splice bar and the splice plate toward each other and thereby to clamp the adjacent edges of said top members between them and to cause said inclined surfaces of said splice plate to engage said corners of said grooves and thereby draw said top members toward each other.

2. In a table top, a plurality of top members and means for splicing the ends of said top members together comprising a T-shaped splice bar

of substantially uniform cross section throughout its length, said top members adjacent their joined ends being rabbeted in their upper surfaces, said splice bar having its arms countersunk in the rabbets of said top members whereby the upper surface of the splice bar is in flush face relation to the upper surface of the top members, said T shaped splice bar having its legs between said top members, with the adjacent edges of the top members spaced from each other a distance greater than the thickness of said leg, said leg having tapped openings spaced longitudinally thereof, a splice plate under said top members, said splice plate having the edges thereof inclined toward said top members, said top members having grooves to receive said edges with the inclined surfaces of said splice plate edges engaging the corners of said grooves, and clamp screws extending through said splice plate and into said tapped openings of said leg of said splice bar to draw the splice bar and the splice plate toward each other and thereby to clamp the adjacent edges of said top members between them to cause said inclined surfaces of said splice plate to engage said corners of said grooves and thereby to effect drawing of said top members toward each other and to effect drawing of the vertical faces of said rabbets into tight engagement with the terminal edges of said arms of said splice bar.

SERN MADSEN.
